COMBINED YARN BOBBIN AND NEEDLE SIZE GAUGE

John Scott Black, Santa Monica, Calif.

Substituted for abandoned application Serial No.
149,419, November 1, 1948. This application
July 17, 1952, Serial No. 20,687

Term of patent 14 years

(Cl. D3—19)

To all whom it may concern:

Be it known that I, John Scott Black, a citizen of the United States residing at Santa Monica, in the county of Los Angeles and State of California, have invented a new, original, and ornamental Design for a Combined Yarn Bobbin and Needle Size Gauge, of which the following is a specification, reference being had to the accompanying drawing forming a part thereof.

Figure 1 is a front perspective view of a combined yarn bobbin and needle size gauge, showing my new design;

Figure 2 is a rear elevational view; and
Figure 3 is an edge elevation view thereof.

This application is a substitute for applicant's abandoned application, Ser. No. D. 149,419, filed November 1, 1948.

I claim:

The ornamental design for a combined yarn

bobbin and needle size gauge, substantially as shown and described.

JOHN SCOTT BLACK.
